UNITED STATES PATENT OFFICE.

CHARLES LARDNER, OF TOPEKA, KANSAS.

DREDGER.

SPECIFICATION forming part of Letters Patent No. 429,351, dated June 3, 1890.

Application filed February 4, 1890. Serial No. 339,131. (No model.)

To all whom it may concern:

Be it known that I, CHARLES LARDNER, of Topeka, in the county of Shawnee and State of Kansas, have invented certain new and useful Improvements in Dredgers; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain improvements in dredges or excavators.

The object of the invention is to provide an improved excavating or dredging bucket of the type known as "clam-shell," and which shall be cheap, simple, and durable in construction, and certain, sure, and automatic in operation. These objects are accomplished by, and my invention consists in, certain novel features of construction, and in combinations of parts more fully described hereinafter, and particularly pointed out in the claims.

Referring to the accompanying drawings, Figure 1 is an elevation of the excavating-bucket and its supporting and conveying apparatus, the bucket being shown closed. Fig. 2 is a detail perspective showing the bucket open, one shell of the bucket being partially broken away. Fig. 3 is a section through the two sliding blocks which operate the bucket, showing the same locked together. Figs. 4, 5, and 6 are respectively an end view, a longitudinal section, and a top plan of the carrying-car with the supporting-pulleys removed.

This bucket is adapted for dredging under water or excavating on land, or wherever the soil or material is soft or sandy and can be readily picked up by the bucket. The conveying and operating construction illustrated in the drawings consists of an elevated supporting or track rope or cable *a*, extending from the spot from which the earth is to be removed to wherever the earth is to be deposited or dumped. Where the apparatus is to be used as a dredger, a suitable support (not shown) is erected over the portion of the bottom of the body of water to be dredged. The supporting-track is secured at one end

to this support extending above the water, and at the other end to a support on the shore, and so that the track is inclined from the shore toward the water-support. A stop-block *b* is carried by said track-cable over the portion of the bottom to be dredged, and is provided with a projecting barbed or shouleder arm *c*, extending, preferably, parallel with the track.

The excavating-bucket is supported and suspended from the conveying car or carriage *d*. This car is supported by hangers *e*, containing pulleys *f*, running on the upper surface of the track-cable. The body of the car suspended from the track is hollow and contains a pair of vertical pulleys *g*. The bucket supporting and operating cable *h* extends from the position of the operator on the shore or dumping-place, where it is provided with suitable operating means, to the traveling car, and into the same between the guide-pulleys *i* and over one of said pulleys *g*, and down and around a vertical pulley *j*, carried by the sliding supporting-block *k* of the bucket, and then up around the other pulley *g* of the conveying-car, and down again and secured at its end to said main sliding block *k*.

The bucket consists of the two similar shells *l*, preferably sharpened at their lower and meeting edges and adapted to swing apart, as shown in Fig. 2, to open the bucket or swing together, as shown in Fig. 1, and close the bucket. At the upper sides of their ends these shells are provided with the links *m*, rigidly secured to the ends of the shells, and at their outer free ends pivoted to the opposite ends of a horizontal cross bar or head *n*, rigidly secured to the lower end of a vertical central shaft or main bar *o*, extending upwardly from the cross-head, and of a suitable length, as shown. The main supporting-block *k* is confined and adapted to freely slide longitudinally on said main bar of the bucket. The vertical pulley *j*, before mentioned, is journaled in the upper open portion of this block. A socket *p* extends up from the bottom of said block, and near its upper end is provided with a beveled shoulder *q*. A vertically-swinging latch-lever *r* extends through the upper open portion of the block, and is pivoted thereto at one end,

while its opposite end extends outwardly therefrom, and is preferably weighted, as shown at *s*, to hold the lever in its normal horizontal position. (Shown in Fig. 3.) This lever is provided with a lug or arm *t*, extending down into the top of the socket or opening *p*, leaving a narrow space between itself and shoulder *q*. Another block *u* is confined to slide longitudinally on said main vertical bar below the main block *k* to close and open the shells of the bucket. A pair of cross-links *v v* are at their lower ends rigidly secured, respectively, to the bottom of each shell, and extend upwardly and radially from the same, and the upper end of each link *v v* is connected with the bucket opening and closing slide-block by means of the links *a' a'*, which, at their opposite ends are pivoted to said block and the upper free ends of said rigid links. A pivoted shouldered latch *b'* extends up from the block *u* and is adapted to enter the socket *p*, and thereby lock the two slides together, as the beveled shoulder of the latch is held on the beveled shoulder *q* by means of the arm *t* of the latch-lever.

The operation of the device is as follows, viz: Suppose the bucket to be filled and raised and on its way to the dumping-ground, as shown in Fig. 1. When the bucket arrives over the dumping-ground, the cord *c'*, attached to the free end of the latch-locking lever and extended up between the rollers in the conveying-car to the operator's stand, is pulled, thereby raising such lever and disengaging its locking-arm *t* from the latch, whereupon the latch *b'* will slip from the main slide by reason of the shoulder *q* and the downward pull on the shell-closing slide through the medium of toggle-links *v* and *a'*, caused by the constant tendency of the shell to swing apart and open, and the shell-closing slide will move down the main vertical bar and the shells will be automatically swung apart and dump their load. The toggle-links, when the bucket is open, fold down, as shown in Fig. 2. These links are so arranged that when the block *u* is drawn up on the bar *o* the secured ends of links *v* will be drawn together, and when said block slides down the secured ends of said links will separate and the shells open. When the bucket is closed and the shell-closing slide is released, the shell will automatically open, because the means then supporting the shells are secured to the outer edges of said shells and consist of the chains *d'*, secured to the outer and upper corners of said shells and to the main slide-block, and having the cross-chains *e'* secured to the cross-bars *n* of the shaft or bar *o*. These cross-chains limit the parting swing of the shells, while the chains *d'* support the shells when open, while the toggle-links mainly support them when closed. After the load has been dumped the open bucket is started back toward the dredging-point, the rope *h* and the block-re-

leasing cord *c'* being paid out as the bucket travels away from the operators. When the bucket arrives over the spot to be dredged, the arm *c* of the stop-block *b* enters car *d* and raises the swinging wing *g'*, thereby allowing the stop *h'* on the supporting and operating rope to pass the same, Fig. 3, and hence allowing the bucket to automatically lower as the rope *h* is paid out. When the bucket strikes the bottom, the operating-rope continues to pay out, and the main slide of the bucket then drops by gravity onto the shell-closing slide, thereby automatically locking the two slides together by reason of the latch before mentioned. The bucket is caused to pick up its load by pulling on the raising and operating rope, thereby drawing up the main slide, and with it the shell-closing slide, and by reason of the peculiar arrangement of the toggle-links the shells are caused to close together and at the same time pick a full load of sand or earth by reason of the arrangement of the digging-edges. When the loaded bucket is raised to the proper point, the stop *h'* engages the movable tube *i'* and draws the same outwardly, thereby raising the spring-pawl *j'* from the shoulder of arm *c*, through the medium of flexible connection *k'*, and releasing the car *d*, so that the car and bucket can be pulled to the dumping-point.

The peculiar conveying apparatus is claimed in an application, Serial No. 296,472, filed December 24, 1889. This bucket is not limited to use with this peculiar conveying apparatus.

It is evident that certain changes might be made in the form and arrangements of the parts described without departing from the spirit and scope of my invention; hence I do not wish to limit myself to the exact construction herein set forth.

What I claim is—

1. The combination of the main upright bar having the cross-bar, the clam-shell having rigid arms hinged to said cross-bar, the main slide and chains extending therefrom to the outer edges of said shells, having cross-chains to limit the parting swing of said shells, and the slide to open and close the shells.

2. In a clam-shell bucket, the combination of the upright bar having a cross head or rod on its lower end, the two clam-shells having rigid arms pivoted on said cross-bar, the shell-operating toggle-links rigidly secured to the bottoms of said shells, a slide on said bar, to which said links are pivoted, and a main supporting-slide on said bar provided with supporting-connections to the outer edges of said shells, substantially as described.

3. In combination, the main upright bar having a cross-head on its lower end, the two clam-shells hinged to said cross-head, the shell operating slide on said bar connected with the bottoms of said shells by toggle-links, the main supporting-slide on said bar

provided with flexible connections to said shells, and means for locking said slides together, substantially as described.

4. The combination of the main upright bar, the hinged clam-shells, a slide on said bar for operating the shells, the toggle-links pivoted to said slide and rigidly secured to and extending radially from the bottoms of said shells, the main slide having flexible supporting-connections to the outer edges of said shells, and a latch for locking said slides together, substantially as described.

5. In combination, the upright bar having a cross-head on its lower end, the clam-shells 15 having rigid arms pivoted on said cross-head, the shell-operating slide on said bar, toggle-links pivoted to said slide and secured to the bottoms of said shells, the main slide, means 20 to lock said slides together, and flexible supporting-connections from the main slide to the outer edges of said shells, provided with cross-connections secured to said cross-head, substantially as described.

6. In combination, the main upright bar, 25 the hinged clam-shells, the main supporting-slide on said bar, flexible supporting-connections from said slide to the outer edges of the shells, the shell-operating slide connected to the bottoms of said shells to close the same, 30 a latch carried by said slide to engage a shoul-

der on the main slide, and a lever to release said latch from the shoulder, substantially as described.

7. In combination, the upright bar having a cross-head on its lower end, the two clam-shells having rigid arms secured rigidly thereto and pivoted to the ends of said cross-head, the main supporting-slide on said bar connected with the outer edges of said shells by chains, the arms rigidly secured to and 35 extending radially from the bottoms of said shells, and the shell-operating slide connected with said radially-extending arms, substantially as described.

8. In combination, the upright bar, the clam-shells carried thereby, the main supporting-slide suspended from the operating-cable and having a beveled shoulder, the shell-operating slide having an upwardly-extending pivoted latch to engage said shoulder and hold the 40 shells closed, and a locking-lever carried by the main slide to hold said latch on a shoulder provided with an operating-connection.

In testimony that I claim the foregoing as my own I affix my signature in presence of 45 two witnesses.

CHARLES LARDNER.
